(57) **CLAIM**

The ornamental design for a hydraulic spreader, as shown and described.

DESCRIPTION

FIG. 1 is a front, top, and right-side isometric view of a hydraulic spreader showing the new design with the jaws of the hydraulic spreader in a closed position.

FIG. 2 is a right-side elevation view of the jaws of the hydraulic spreader.

FIG. 3 is a top plan view of the jaws of the hydraulic spreader.

FIG. 4 is a bottom plan view of the jaws of the hydraulic spreader.

FIG. 5 is a front elevation view of the jaws of the hydraulic spreader.

FIG. 6 is a front elevation view of the entire hydraulic spreader.

FIG. 7 is a front, top, and right-side isometric view of the hydraulic spreader with the jaws in an open position.

FIG. 8 is a right-side elevation view of the jaws in the open position.

FIG. 9 is a top plan view of the jaws in the open position; and,

FIG. 10 is an enlarged fragmentary view of the end of the jaws identified in FIG. 1.

The broken lines in the figures depict portions of the hydraulic spreader that form no part of the claimed design. The broken line circle near the top of FIG. 1 identifies the portion seen in larger scale in FIG. 10.

1 Claim, 10 Drawing Sheets
